UNITED STATES PATENT OFFICE

90,791

DESIGN FOR A CLOCK CASE

Arthur Edwin Wrench, Woodside, N. Y., assignor
to Warren Telechron Company, a corporation of
Maine

Application August 12, 1933. Serial No. 49,008

Term of patent 14 years

To all whom it may concern:

Be it known that I, ARTHUR E. WRENCH, a subject of the King of England, residing at Woodside, county of Queens, State of New York, have invented a new, original, and ornamental Design for a Clock Case, of which the following is a specification, reference being had to the accompanying drawing, forming a part thereof.

Fig. 1 is a front perspective view of a clock case showing my new design; and Fig. 2 is a front perspective view, on a reduced scale, from

another angle to that shown in Fig. 1, with the surface ornamentation omitted from the case and also the numeral markings omitted from the clock dial.

I claim:

The ornamental design for a clock case as shown and described.

In witness whereof, I have hereunto set my hand this 1st day of August, 1933.

ARTHUR EDWIN WRENCH.
